UNITED STATES PATENT OFFICE.

CLYDE A. HUGHES, OF DANVILLE, VIRGINIA.

ADVERTISING DEVICE.

Application filed June 23, 1923. Serial No. 647,238.

To all whom it may concern:

Be it known that CLYDE A. HUGHES, a citizen of the United States, residing at Danville, in the county of Pittsylvania and State 5 of Virginia, has invented certain new and useful Improvements in Advertising Devices, of which the following is a specification.

This invention relates to advertising devices, and has particular reference to devices of that kind commonly known as changeable sign exhibitors.

The primary object of the invention is to provide novel and improved means for successively moving a plurality of signs to different points for exposing advertising matter on both faces thereof, and automatic means for momentarily bringing the signs to rest at these points so that the advertising 20 matter may be easily read by the observer.

Another object of the invention is to provide a plurality of signs having reading matter on both faces thereof and extended for rotation about a horizontal axis, means 25 for elevating the rearmost sign in a horizontal position, means for momentarily retaining the innermost sign at rest in this horizontal position so that the reading matter on one face of the same may be readily 30 observed, said last named means being automatically returned to operative position for further feeding the same to a vertical position for exposing the other face of said sign, means for automatically releasing the other 35 face of said sign, when vertically disposed for allowing the sign to remain in this position momentary so that the reading matter on said opposite face of the sign may be read, separate means for swinging the sign rearwardly in position to be engaged by the first 40 named means, means operated by upward swinging motion of the rearmost sign for momentarily rendering the rearward swinging means inoperative for allowing the forward most vertical sign to remain momentary at 45 rest.

Still another object of the invention is to generally simplify an improved device of the above kind whereby a simple and durable 50 construction is presented for advertising purposes at a minimum cost.

With the above general objects in view, and others that will become apparent as the 55 nature of the invention is better understood, the same consists in the novel form, combination and arrangement of parts hereinafter

more fully described, shown in the accompanying drawings and claimed.

In the drawings, wherein like reference characters indicate corresponding parts throughout the several views;

Figure 1 is a longitudinal sectional view through the casing of a display device constructed in accordance with the present invention, with the mechanism thereof shown in side elevation.

Figure 2 is a view in horizontal section through the casing of the device shown in Fig. 1 with the mechanism shown in top plan, and

Figure 3 is an enlarged fragmentary perspective view illustrating details of the invention.

Referring more in detail to the several views, the invention preferably embodies a suitable casing 5 having an opening 6 in the front wall thereof and an opening 7 in the top wall thereof engaged with the opening 6, through which openings the signs are adapted to be displayed in a manner which will presently become apparent.

Suitably mounted within the casing 5 adjacent one side thereof is a motor 8 having a horizontal shaft 9 which projects towards the other side of the casing and has a bevel gear upon the free end thereof as at 10 and which mesh with a further bevel gear 11 fixed upon the lower end of a vertical shaft 12 which has a bevel gear 13 upon its upper end in mesh with a bevel gear 14 fixed upon a horizontal shaft 15 suitably mounted above the shaft 9. The shafts 9 and 15 are supported in a frame 16 which also include a forward member having a horizontal transversely extending rod 17 mounted therein at the forward end of the casing and one end portion of this rod has a plurality of signs 18 loosely suspended therefrom so as to be capable of being rotated thereabout, which signs are adapted to have reading matter on both faces thereof. A tubular shaft 19 is rotatably mounted upon the other end portion of the rod 17 and has a disc 20 fixed to the inner end thereof adjacent one side of the sign, and the inner face of the disc 20 is provided with a tube 21 that projects inwardly from the margin of the disc as shown in Fig. 3. Slidably disposed within the tube 21 is a tubular catch element 22 which is normally pressed outwardly by means of a spring 23 arranged within the tube 21 and bearing against the inner end of the catch

22. The tube 21 is provided with a longitudinal slot 24 through which projects a depending pin 25 fixed to the tubular catch 22, and this pin is arranged to engage the 5 curved outer edge of a cam element 26 suitably mounted in the position shown in Fig. 1 at the inner side of the disc 20. The adjacent sides of the signs 18 have outwardly projecting lugs 27 onto which the latch element 22 is adapted to be slid by the spring 24 when the latch element is released from the cam 25. It will be seen that the cam 26 is so positioned as to cause outward movement of the tubular latch 22 when the latter is disposed adjacent the depending signs, and the pins 25 will ride off of this cam when the latch 22 is forced adjacent the rearmost sign so that the spring 24 will then be free to project said catch onto the lug 27 of the rearmost sign in order to enable this sign to be lifted upon rotation of the disc 20 without influencing the positions of the remaining signs. A ratchet wheel 28 is fixed upon the tubular shaft 19 outwardly of the disc 20 and is adapted to be actuated by a relatively long pawl 29 operatively associated with an eccentric 30 fixed upon the shaft 15 hence it will be observed that forward movement of the pawl 29 causes partial rotation of the ratchet wheel 28 while rearward movement of the coil has no effect on said ratchet wheel. Means is provided for raising the pawl 29 to inoperative position when the rearmost sign reaches a horizontal position beneath the opening 7 so that the sign will be at rest in this position for a sufficient length of time to enable an observer to read the matter thereon. This means embodies a cam element 31 mounted upon a shaft 32 which is carried by the frame 16 at a point between the cam 15 and the rod 17 as shown in Figs. 1 and 2. This cam element is rotated by means of a pawl 33 operated by an eccentric 34 on the shaft 15 and cooperating 45 with a ratchet wheel 35 fixed on the shaft 32. It will be seen that when the raised portion of the cam element 31 passes the pawl 29, the latter will automatically again lower by gravity and assume its operative relation with the ratchet wheel 28 for again continuing the rotation of the disc 20 to carry the signs further around until they assume a vertical suspended position rearwardly of the opening 6 in the front of the casing. 50 At this point in the operation of the device, a sign will have reached a horizontal position beneath the opening so that the reading matter on the rear face thereof may be read, while another sign is rearwardly of the opening 6 for preventing observation of the reading matter on the front face of the same, the disc 20 being at rest at that time due to the pawl 29 being held elevated by the cam 31. When the pawl 29 is again 55 returned to operative position, the vertical

foremost sign is carried rearwardly a slight distance until the cam 26 disengages the catch 22 from the lug 27 of said sign and means is then provided for feeding the sign rearwardly for a slight distance until the latch element 22 is in position to engage the lug 27 of the rearmost sign. This means employing an endless belt 36 which passes around a relatively large wheel 37 fixed upon a shaft 38 which is mounted in the frame 16 beneath the signs 18, which end is provided with ratchet mechanism 38' which prevents movement of the shaft 38 but permits free rotation thereof toward the right of Fig. 1. The endless belt 36 also passes around a smaller wheel 39 fixed upon a point journaled in the frame 16 forwardly of the shaft 38, and the belt 36 is provided with a plurality of uniformly spaced outwardly projecting fingers 41 adapted to engage the lower ends of the signs 18 as shown in Fig. 1 for swinging them a slight distance rearwardly. The shaft 38 is rotated by means of a pawl 42 operated by an eccentric 43 on the shaft 9 and engaging a ratchet wheel 44 which is fixed on the shaft 38, it being noted that the pawl 42 turns the wheel 44 when moving rearwardly, but does not influence or turn said wheel when moving forwardly, thus causing the upper plate of the feeding device to move rearwardly as is necessary in swinging the signs rearwardly. Means is provided for momentarily rendering the sign swinging means embodying the endless member 36 inoperative, and this means includes a lever 45 fixed upon a shaft 46 mounted in the frame 16 beneath the shaft 32 and having its forward end provided with an anti-friction roller 47 arranged in the path of the rearmost sign, the other end of said lever 45 being weighted as at 48 so as to bring the arm 35 at rest substantially in the position shown in Fig. 1. As shown in the latter figure, the catch 22 is engaged with the lug 27 of the rearmost sign and the disc 20 is rotated so as to swing this rearmost sign upwardly to a horizontal position. When this takes place, the forward end of the lever 45 is caused to swing upwardly so as to rotate the rock shaft 46. This movement of the rock shaft 46 is transmitted to a cam 49 fixed thereon and arranged beneath the pawl 42 so that said pawl is released from the ratchet wheel 44 and the foremost depending sign is allowed to remain stationary for a period of sufficient length to permit the reading matter thereon to be read through the front opening 6. 100 Means is provided for holding the shaft 19 against accidental rotation as the same is intermittently rotated by the pawl 29, and this means may consist in a wheel 50 fixed on the tubular shaft 13 and having a scalloped or irregular edge or margin forming teeth spaced apart a distance equal 105 110 115 120 125 130

to the spaces of the teeth on the ratchet wheel 28, which teeth are adapted to be engaged by an anti-friction element 51 carried by a spring pressed plunger 52 mounted on the frame 16, which plunger is normally urged towards the wheel 50 by means of the spring 53 as seen in Fig. 3. The motor 8 is placed into operation by turning the shaft 9 towards the right, and through 10 the gearing described, the shaft 15 is rotated in an opposite direction the eccentrics actuate the pawls 29 and 42, thus causing movement of the disc 20 and endless member 36. The disc 20 carries the rearmost sign 18 upwardly, and in so doing causes the lever 45 to be swung so that the cam 49 releases the pawl 42 from the ratchet wheel 44, thus rendering the swinging means for the remaining signs inoperative, which 20 swinging means embodies the endless member 36. Thus, the foremost depending sign is allowed to remain stationary so as to be viewed through the opening 6. The movement of the rearmost sign continues until 25 this sign reaches a horizontal position beneath the opening 7 whereupon the cam element 31 raises the pawl 39 and allows the disc 20 to stop so that the sign is allowed to remain in this horizontal position for 30 being viewed through the opening 7. It will be seen that the rotation of the cam element 31 continues until its raised portion passes the pawl 29, thereby allowing the latter to lower by gravity again for operative engagement with the ratchet wheel 28. It is noted that the rearmost sign in swinging upwardly as noted above, causes the same to pass the lever 45 so that the latter swings downwardly to permit the pawl 42 40 to engage with the ratchet wheel 44 so that the remaining signs are then swung rearwardly after sufficient time has elapsed for allowing the foremost sign to have been read through the opening 6. The rotation of the disc 20 is then continued so as to swing the sign from the position beneath the opening 27 around to a vertical position behind the opening 6. In doing this the pin 25 encounters the cam element 26 and is released or moved outwardly thereby so as to disengage the latch 22 from this sign. The disc 20 then continues its rotation past the remaining depending sign until it again reaches the position shown in Fig. 1 where- 50 in the pin 25 has ridden off of the cam element 26 and the latch 22 has again been projected to engage the lug 27 of the rearmost sign.

From the foregoing description, it is believed that the construction and operation as well as the advantages of the present invention will be readily understood and appreciated by those skilled in the art. 60

Minor changes may be made without departing from the spirit and scope of the invention as claimed. 65

What I claim as new is:—

1. In a changeable sign exhibitor, means for suspending a plurality of signs for rotation about a horizontal axis, a plurality of signs suspended by said means and having laterally projecting lugs upon the adjacent sides thereof, a rotatable disc disposed beside the signs outwardly of the lugs thereof and having a spring pressed tubular catch projecting towards the lugs in the path of the latter, means for rotating said disc, and a fixed cam arranged in the path of the tubular catch for moving the latter out of the path of the lugs of all but the rearmost one of said signs, means at the lower edges of said signs for swinging all but the rearmost one of the same a slight distance rearwardly, and means automatically operated by the upper swinging movement of the rearmost sign for rendering said sign swinging means momentarily inoperative. 70 75 80 85

2. In a changeable sign exhibitor, means for suspending a plurality of signs for rotation about a horizontal axis, a plurality of signs suspended by said means and having laterally projecting lugs upon the adjacent sides thereof, a rotatable disc disposed beside the signs outwardly of the lugs thereof and having a spring pressed tubular catch projecting towards the lugs in the path of the latter, means for rotating said disc, and a fixed cam arranged in the path of the tubular catch for moving the latter out of the path of the lugs of all but the rearmost one of said signs, means at the lower edges of said signs for swinging all but the rearmost one of the same a slight distance rearwardly, and means automatically operated by the upper swinging movement of the rearmost sign for rendering said sign swinging means momentarily inoperative. 90 95 100 105 110

In testimony whereof I affix my signature.

CLYDE A. HUGHES.
